UNITED STATES PATENT OFFICE.

OLIN W. BLACKETT, OF BROOKLINE, MASSACHUSETTS.

HEADLIGHT.

1,397,793.

Specification of Letters Patent.

Patented Nov. 22, 1921.

Application filed January 10, 1921. Serial No. 436,383.

To all whom it may concern:

Be it known that I, OLIN W. BLACKETT, a citizen of the United States, residing at Brookline, in the county of Norfolk and 5 Commonwealth of Massachusetts, have invented certain new and useful Improvements in Headlights, of which the following is a specification.

This invention relates to headlights such 10 as are used on automobiles and other vehicles.

Such headlights as usually constructed, are provided with reflectors which project 15 the rays of light so directed as to shine fully in the eyes of persons facing the front of the automobile, the glare of the headlight having a tendency to blind or confuse them.

The object of my improvement is to limit 20 the field of illumination and confine the major portion of the rays of light to an area below the axis of the headlight, thus reducing and largely eliminating the glare of the light projecting above the axis of the said light without impairing the illumination of 25 the roadway in front of the headlight.

I attain this object in the manner illustrated in the accompanying drawing, in which Figure 1 is a front elevation of the headlight; Fig. 2 is a central vertical section 30 of the headlight on the line 2—2, Fig. 1; and Fig. 3, a detail view in perspective of the non-reflecting semi-cylindrical laminae and the radial supporting laminae.

Similar letters refer to similar parts 35 throughout the several views. The parabolic reflector P, the surface of which is generated by the revolution of a parabola about its axis through an angle of 180 degrees is placed beneath a confocal elliptical reflector E, the surface of which is generated by the revolution of an ellipse about its major axis through an angle of 180 degrees, the axis of the two reflectors being coincident, the eccentricity of the parabola and 45 the ellipse being so taken that the vertex of the parabola lies between the common focus and that vertex of the ellipse which is nearest to the common focus, the surface of the parabolic reflector meeting 50 the surface of the elliptical reflector at points considerably forward of the common focus. A horizontal crescent-shaped shelf or plate S of a suitable size joins and supports the parabolic and elliptical reflectors, P and E. At or near the vertex of the 55 parabolic reflector P is an opening of suffi-

cient size and suitable shape to admit the insertion of a lighting socket. The parabolic and elliptical reflectors P and E, extend forward of their common focus only to the 60 points at which their surfaces meet, the forward ends of the said reflectors being secured to a tubular or cylindrical reflector C whose axis coincides with the axis of the headlight. The elliptical reflector is adjusted so that the 65 forward focus of the said elliptical reflector will be in the vicinity of the front of the headlight, either inside or outside of it as desired.

The front of the headlight is provided 70 with glass G adapted to fit the said front and attached and adjusted thereto in any suitable manner so that the said glass front may be opened and closed when desired so that the lamp in the interior of the headlight may 75 be replaced. All of said glass front above the horizontal diameter thereof is preferably of yellow or amber color, but may be translucent, or covered with any suitable material that will absorb partially the rays 80 of light, excepting therefrom the portion in a small semi-circle D the center of which coincides with the center of the glass front, permitting the rays of light reflected from the elliptical reflector to project without being 85 obstructed.

The lower portion of the interior of the headlight is provided with a series of semi-cylindrical laminae F of any suitable non-reflecting material, concentric with the focal 90 axis of the reflector; these laminae extend backward from the glass front of the headlight, or points adjacent thereto, as desired, to the surface of an imaginary cone, the base 95 of which lies at the intersection of the parabolic and cylindrical reflectors and the vertex of which lies in the focus of the parabolic reflector, the laminae which interfere with the light bulb in the interior of the headlight are shortened slightly so that they 100 will not come in contact with the said light bulb. The semi-cylindrical members are supported by non-reflecting radial laminae R, secured to the interior surface of the cylindrical reflector. A suitable casing A 105 encloses the reflectors and is adapted to be fastened to the vehicle.

It will be readily seen and understood that by the arrangement of the several parts as shown and above described that light 110 striking the parabolic reflector is projected parallel to the focal axis, and light striking

the elliptical reflector is projected through the forward focus onto the roadway, and the reflectors are concealed by the translucent glass front and the lamineæ when observed 5 from a point in front of and above the head-light.

Having thus described my invention, I claim and desire to secure by Letters Patent—

10 In a headlight, the combination of a casting, a parabolic reflector, an elliptical reflec-

tor, a cylindrical reflector, a source of light, said reflector being adapted to throw the light ahead, a series of semi-cylindrical, non-reflecting, parallel lamineæ in the lower portion of the headlight, a series of radio lamineæ, supporting the semi-cylindrical lamineæ, and a glass front, the upper major portion of which is translucent, all substantially as described. 15

OLIN W. BLACKETT.
